UNITED STATES PATENT OFFICE.

EDWARD S. PRESTON, OF CHICAGO, ILLINOIS, ASSIGNOR TO EDMUNDS & JONES CORPORATION, A CORPORATION OF NEW YORK.

DESIGN FOR A SIGNAL-LAMP LENS.

61,347.

Specification for Design.

Patented Aug. 8, 1922.

Application filed October 12, 1921. Serial No. 507,387. Term of patent 3½ years.

To all whom it may concern:

Be it known that I, EDWARD S. PRESTON, a citizen of the United States, residing at Chicago, in the county of Cook and State of Illinois, have invented a new, original, and ornamental Design for a Signal-Lamp Lens, of which the following is a specification, reference being had to the accompanying drawings, forming part thereof.

The figure is an elevation of a signal lamp lens, showing my new design.

I claim:

The ornamental design for a signal lamp lens, as shown.

EDWARD S. PRESTON.
